SEWING-MACHINE HOOK MECHANISM

Richard K. Hohmann, Jamaica, N. Y., assignor
to White Sewing Machine Corporation, Cleve-
land, Ohio, a corporation of Delaware

Application January 15, 1945, Serial No. 572,931

6 Claims. (Cl. 112—228)

1
The general object of the present invention is to provide an improved sewing machine mechanism of the type in which a needle thread loop is passed around a bobbin holder by a rotary hook. The term rotary hook as used herein generically includes a revolving hook which in operation turns continuously in one direction, and an oscillating hook which turns back and forth about an axis through an arc which ordinarily is slightly greater than 180°.

More specifically stated, the general object of the invention is to provide a sewing machine mechanism comprising a hook turning about a vertical axis and formed with a chamber open at its upper end and a bobbin holder normally received in said chamber, and in which the hook and bobbin holder have cooperating guide surfaces through which the bobbin holder is normally held by gravity in operative relation with the hook, and which permit the bobbin holder to be moved vertically into and out of the bobbin holder chamber. In a preferred form of the invention, a guard member is mounted on the supporting frame work for movement into and out of a position in which it extends over the bobbin holder without normally engaging the latter, but is operative to prevent the holder from moving up out of its normal position as a result of vibration or some abnormal operating condition.

A specific but practically important object of the present invention is to provide an oscillating hook mechanism having the above mentioned characteristics and comprising elements so disposed, and having their movements so timed that the tendency of the bobbin holder to share oscillating movements of the hook as a result of their frictional engagement, is utilized to open a thread passage between the bobbin holder and a stationary retainer element to accommodate the movement of the needle thread loop into the space between the bobbin holder and retainer element at the beginning of each loop forming operation, and to open a second thread passage between said holder and retainer for the escape of the thread loop as each loop is being completed.

The various features of novelty which characterize my invention are pointed out with particularity in the claims annexed to and forming a part of this specification. For a better understanding of the invention, however, its advantages and specific objects attained by its use, reference should be had to the accompanying drawings and descriptive matter in which I have

illustrated and described preferred embodiments of the invention.

Of the drawings:

Fig. 1 is a plan view of an oscillating hook and 5 associated bobbin holder with the hook in the position occupied at the beginning of its loop drawing movement;

Fig. 2 is a view taken similarly to Fig. 1 but 10 omitting parts shown in Fig. 1, and showing the hook at the end of its loop drawing movement and the loop fully expanded;

Fig. 3 is a view similar to Fig. 2 and showing the hook in the same position, but showing the loop in a later, much contracted condition;

15 Fig. 4 is a view taken similarly to Fig. 2, but with the hook in the position occupied after a slight return movement from the position shown in Fig. 3;

Fig. 5 is an elevation in section on the broken 20 line 5—5 of Fig. 1;

Fig. 6 is an inverted plan view of the bobbin holder; and

25 Fig. 7 is an inverted plan view of the mechanism giving oscillating movements to the vertical hook shaft.

In the form of construction shown in the drawing, a vertically disposed hook shaft 1 is given oscillating movements by means comprising an arm 3 secured to the shaft 1 adjacent its 30 lower end, and a link 4 connecting the free end of the arm 3 to one end of an oscillating lever 5. The latter is journaled on a stationary stud shaft 5'. The second end of the lever 5 is connected by a pivot 6 to one end of the link 7. 35 The latter is adapted to be given reciprocatory movements in the general direction of its length in timed relation with those of an associated, vertically movable needle and needle reciprocating mechanism. Said mechanism is not illustrated and need not be further described as it 40 forms no part of the present invention and may be of old and well known type.

At its upper end the hook shaft supports and 45 is rigidly connected to a loop-taker or hook member 8. The latter as shown is in the form of a shallow cup shaped body coaxial with the shaft and having an apertured bottom wall 9, and is characterized by the fact that its upper end portion 10 is in the form of a thin cylindrical flange or rib coaxial with the shaft 1. The lower end of the flange portion or rib 10 is surrounded by an annular horizontal bearing surface 11. The rib 10 is cut away at opposite sides of the shaft 1 to form thread notches 12 and 13. The 50 notch 12 is of such depth that its bottom wall

is below the bearing surface 11. One end wall of the notch 12 is undercut to form a hook 14 adapted to take a thread loop from the coating needle, when the latter is in the position in which it extends downward through the work and needle hole in the needle plate. The work and needle plate are not shown but the dotted circle 15 represents the outline of the needle hole. The two end walls of the notch 12 are oppositely inclined to one another and to a plane radial to the hook shaft and passing between said walls, so that the outer ends of said walls are more widely separated than are their inner ends. The notch 13 at the opposite side of the loop-taker from the notch 12 may be formed wholly in the rib 10 with its bottom edge slightly above the bearing surface 11.

The annular rib or flange 10 and the surrounding bearing surface 11 provide supporting and guiding surfaces for a bobbin holder 16. The latter is formed with a cup shaped chamber 17 open at its upper end to receive a thread bobbin 18 which may be of conventional form. As shown, the vertical axis of the bobbin chamber 17 is laterally displaced from the axis of the hook shaft 1. The bobbin holder includes an arc shaped flange portion 19 extending radially away from the wall of the bobbin chamber at the side of the latter remote from the axis of the hook shaft. The underside of the flange 19 forms a horizontal bearing surface which is above and in engagement with the bearing surface 11 of the loop taker 8 in the operating condition of the apparatus. An arc shaped groove 20 coaxial with the shaft 1 and having the same radius of curvature as the rib 10, is formed in the flange 19. The groove 20 extends upward from the bottom side of the flange 19 and is shaped and proportioned to receive a corresponding portion of the loop taker cylindrical rib 10. In operation, the bobbin holder 16 is thus accurately positioned in the loop taker. At one end, the flange 19 is cut away to form a spaced apart pair of horn portions 21 and 22.

The bobbin holder 16 is prevented from sharing the general angular movements of the oscillating hook 8 by a retaining element 22'. The latter comprises a plate-like body portion held stationary by screws 23 at the outer side of the rotary hook, and comprises an arm 24 extending under the horn 22 and terminating in a vertically disposed thread guide portion 25 with its upper end portion loosely received between the horn portions 22 and 21 of the flange 19. As shown, the thread guide part 25 is shaped to form a vertical trough shaped needle channel open at its outer side. The side walls of said needle channel are located at opposite sides of the plane including the axis of the hook shaft 1 and the axis of the opening 15 in the needle plate member. The horns 21 and 22 and the part 25 are proportioned and disposed to provide a clearance space, serving as a thread passage between the guide 25 and one or the other of the horns 21 and 22 in regular alternation as hereinafter explained.

A lever element 30 journaled on the stationary pivot 31 normally extends over the flange portion 19 of the bobbin holder without directly engaging the latter, but separated therefrom by a distance too small to permit objectionable movement of the bobbin holder up from its normal position in the hook as a result of vibration or other abnormal condition which may occasionally develop. As shown, the arm 30 is biased by a spring 32 to turn from the full line position into

the dotted line position shown in Fig. 1. In the latter position, the arm 30 does not extend over the bobbin holder. The arm 30 is normally held in its full line position by a latch member 34 in engagement with a hook portion 33 of the arm 30. The member 34 is mounted on a stationary pivot 35 and biased by a spring 36 for movement into its latching position. As shown in Fig. 5, the juxtaposed surfaces of the arm 30 and bobbin holder flange 19 are similarly inclined to the loop-taker axis and are separated by a clearance space through which the thread loop drawn by the beak 14 may freely pass.

In operation, the loop-taker beak or hook 14 engages the needle thread 40 as it moves counter-clockwise from its position shown in Fig. 1. As the counter-clockwise movement of the hook progresses, the needle thread loop is moved through the space between the retainer part 25 and the horn 21, and the upper side of the loop is drawn over the top of the bobbin holder, while the under side is drawn under the bobbin holder. As the counter-clockwise movement continues and the hook approaches the position shown in Fig. 2, the needle thread loop is drawn away from the hook by the take-up mechanism of the sewing machine which then rapidly contracts the loop and finally pulls it off the horn 22.

As the hook begins to turn in the counter-clockwise direction, the bobbin holder moves with the hook under the action of friction to open the previously closed clearance between the horn 21 and retainer 25, thereby providing the open thread passage shown in Fig. 1 through which the thread loop passes preparatory to its movement about the body of the bobbin holder. Similarly when the hook starts to move clockwise back from its position shown in Fig. 2, the bobbin holder is moved through the small angle necessary to bring the horn 21 into engagement with the retainer 25 and to separate the horn 22 from the retainer. This provides a clearance space or thread passage through which the needle thread loop passes as shown in Fig. 4, as the loop is being drawn off the horn 22 and tightened up around the portion of the bobbin thread 41 extending from the bobbin thread tension spring 42 carried by the bobbin holder, to the underside of the portion of the work directly beneath the needle plate opening 15.

Except during the periods in which the beak 14 is at or adjacent to the ends of its path of movement, and hence is stationary, or is moving with relative slowness, the horns 21 and 22 are directly above and engage the upper edge of the rib 10. The horn 22 is angularly displaced from the groove 20 to a substantial extent as plainly appears in Fig. 6, and the rib 10 and horn 22 thus cooperate to insure against risk of tilting movement of the bobbin holder in the direction to lower the horns 21 and 22. Such tilting movement might otherwise occur when the loop taker is moving at relatively high speed. As previously explained, the thread notch 12 is so located that the rib 10 does not interfere with the movement of the thread loop onto the bobbin holder. The thread notch 13 is so located that the rib 10 does not interfere with the movement of the thread loop off the horn 22 in the final stage of each loop forming operation.

As previously explained, a bobbin holder may be mounted in an open top loop-taker in the general manner shown in the drawing when the loop-taker is of the type revolving continuously in one direction, as well as when the loop-taker oscillates as in the particular construction shown in

the drawings. In accordance with the usual practice of the art, the bobbin holder used with a continuously revolving hook would ordinarily have a bobbin chamber coaxial with the hook. With the continuously revolving hook, however, the frictional tendency of the bobbin holder to share the rotative movement of the looper can not be used to alternately open loop receiving and discharging thread passages for movement of the thread loop over and off of the bobbin holder.

The cooperating cylindrical guide surfaces formed by the walls of the rib 10 and groove 20 are of special utility when a considerable portion of the bobbin holder is cut away so that the cooperative guide surfaces of the bobbin holder and loop-taker are in operative contact through an angle about the loop-taker axis which is substantially less than 360°. As those skilled in the art will realize the cutting away of the bobbin holder shown in the drawings, not only reduces the bobbin holder weight, but facilitates and expedites the movement of the loop off the bobbin holder, and permits the extension of the thread guide support, comprising parts 22' and 24, down through the loop-taker and beneath the horn 22, and the extension of the thread guide part 25 up through the peripheral notch formed in the bobbin holder, and the opposite side walls of which terminate at their outer ends in the horns 21 and 22. The engagement of the upper edge of the rib 10 by the horn 22 contributes to bobbin holder stability notwithstanding the cutting away of relatively large adjacent portions of the bobbin holder. For analogous reasons it is desirable in many cases to cut away relatively large portions of bobbin holders which are coaxial with the loop-taker.

In the arrangement shown the needle axis is parallel to the loop-taker axis and between the latter and the path of movement of the loop-taker beak 14. This permits the bobbin to be located at the left side of the needle as seen from the operator's normal position. This makes the bobbin more accessible than it would be if the entire loop-taker were at the right side of the needle. In the latter case however, the loop-taker could be smaller in diameter than is inherently possible with the arrangement shown.

The relatively large size of the loop-taker required with the arrangement shown augments the need for cutting away a relatively large portion of the bobbin holder and for laterally displacing the bobbin axis from the hook axis, and augments the advantage obtained with the cylindrical guide surfaces formed by the walls of the rib 10 and groove 20.

To control the movement of the thread loop as it passes from the condition shown in Fig. 2 into that shown in Fig. 3, a thread finger 43 secured to the upper side of the part 22 extends over a portion of the bobbin holder adjacent to the arm 24 with suitable clearance. The clearance provided accommodates the passage of the thread loop and permits the direct vertical movement of the bobbin holder required for the engagement and separation of the walls of the slot 20 with the rib 10. With said walls and ribs disengaged, a slight tilting adjustment of the bobbin holder permits the latter to be moved upward away from the loop-taker.

Having now described my invention, what I claim as new and desire to secure by Letters Patent, is:

1. A sewing machine mechanism, comprising 75 vertically movable into and out of the latter, said

in combination a loop taker element turning about a vertical axis and having a bobbin holder seat at its upper side including an uprising rib portion of said element extending circularly about said axis, and a bobbin holder element normally held in engagement with said seat by gravity and vertically movable toward and away from said seat, and formed with a groove in the form of an arc extending circularly about said axis for substantially less than 360°, and entered by said rib, said bobbin holder element having a peripheral portion cut away to form horns separated by a notch and at least one of which is angularly displaced about said axis from said groove and extends over said rib whereby the latter restricts the downward displacement of said horn, and a stationary needle guide extending through said notch and cooperating with said horns to restrict angular movement of the bobbin holder element about said axis in either direction.

2. A sewing machine mechanism comprising in combination a loop taker element oscillating about a vertical axis and comprising a bobbin holder chamber open at its upper side, a bobbin holder element normally received in said chamber and vertically movable into and out of the latter, one of said elements being formed with a cylindrical rib coaxial with said axis and the other of said elements being formed with a groove extending circularly about said axis and entered by said rib and having cylindrical inner and outer walls respectively engaging the inner and outer walls of said rib, said bobbin holder element being cut away to form a peripheral notch, and a stationary bobbin holder retaining member extending through said notch and shaped and disposed to engage the bobbin holder at either side of said notch with clearance between said member and the side of the notch not engaged by said member, whereby the frictional contact of the bobbin holder element with the loop-taker element moves the bobbin holder element to open a thread passage between said member and one side or the other side of said notch on initial turning movement of the oscillating loop-taker element in one or the other direction, respectively.

3. A sewing machine mechanism comprising in combination a loop taker element oscillating about a vertical axis and comprising a bobbin holder chamber open at its upper side, a bobbin holder element normally received in said chamber and vertically movable into and out of the latter, one of said elements being formed with a cylindrical rib coaxial with said axis and the other of said elements being formed with a groove extending circularly about said axis and entered by said rib and having cylindrical inner and outer walls respectively engaging the inner and outer walls of said rib, said bobbin holder element being cut away to form a peripheral notch, and a stationary bobbin holder retaining member comprising an uprising portion extending through said notch and a supporting portion extending into said chamber through its open upper side and extending beneath a portion of the bobbin holder element at one side of said notch.

4. A sewing machine mechanism comprising in combination a loop-taker element turning about a vertical axis and comprising a bobbin holder chamber open at its upper side, and a bobbin holder element normally received in said chamber and vertically movable into and out of the latter, said

elements being formed with cooperating guide surfaces including a cylindrical rib formed on one of said elements and coaxial with said axis and the other of said elements being formed with a groove extending circularly about said axis and entered by said rib and having cylindrical inner and outer walls respectively engaging the inner and outer walls of said rib; said bobbin holder element being cut away to form a peripheral notch and a thread loop discharging horn forming one side wall of said notch and extending over and engaging a guide surface on the loop-taker element.

5. A sewing machine mechanism comprising in combination a loop taker element turning about a vertical axis and comprising a bobbin holder chamber open at its upper side, a bobbin holder element normally received in said chamber and vertically movable into and out of the latter, one of said elements being formed with a cylindrical rib coaxial with said axis and the other of said elements being formed with a groove extending circularly about said axis and entered by said rib and having cylindrical inner and outer walls respectively engaging the inner and outer walls of said rib, and a member movable into and out of a position in which it extends over said bobbin holder element and prevents the latter from moving up out of said chamber.

10
15
20
25

6. A sewing machine mechanism comprising in combination a loop taker element turning about a vertical axis and comprising a bobbin holder chamber open at its upper side, a bobbin holder element normally received in said chamber and vertically movable into and out of the latter, one of said elements being formed with a cylindrical rib coaxial with said axis and the other of said elements being formed with a groove extending circularly about said axis and entered by said rib and having cylindrical inner and outer walls respectively engaging the inner and outer walls of said rib, a member pivoted to turn about an axis from into and out of a position in which it extends over the bobbin holder element and prevent the latter from moving up out of said chamber, said member being biased for movement out of said position, and latching means releasably securing member in said position.
